UNITED STATES PATENT OFFICE.

LEONARD F. FAIRBANKS, OF HOPKINTON, MASSACHUSETTS.

MACHINE FOR UPSETTING WHEEL-TIRES.

SPECIFICATION forming part of Letters Patent No. 771,050, dated September 27, 1904.

Application filed May 14, 1903. Serial No. 157,097. (No model.)

To all whom it may concern:

Be it known that I, LEONARD F. FAIRBANKS, of Hopkinton, in the county of Middlesex and State of Massachusetts, have invented certain new and useful Improvements in Machines for Upsetting Wheel-Tires, of which the following is a specification.

This invention relates to machines for upsetting wheel-tires of the type shown in Letters Patent of the United States No. 554,484, granted to me February 11, 1896. The machine shown in said patent comprises a fixed bed or anvil having a concave tire-supporting surface, a fixed guide located over the anvil, a movable tire-supporting bed adapted to be moved toward and from the anvil, a movable guide located over said movable bed, dogs engaged with the two guides and vertically movable therein, and cams adapted to force said dogs downwardly into engagement with a tire supported by said anvil and bed, and means for operating said cams, means being provided for moving the movable bed and the guide and dog coöperating therewith toward the fixed anvil, so that the portion of the tire interposed between the two dogs may be longitudinally compressed by forcing the movable bed toward the fixed anvil and at the same time hammering the intermediate portion of the tire upon the anvil to take up undulations produced in the tire, all as described in said patent.

My present invention has for its object to provide improved means for operating said dogs, to the end that they may be held positively in any position to which they may be adjusted, and, further, to the end that the machine as a whole may be simplified and rendered more efficient.

The invention consists in the improvements which I will now proceed to describe and claim.

Of the accompanying drawings, forming a part of this specification, Figure 1 represents an end elevation of a tire-upsetting machine embodying my improvements. Fig. 2 represents a front elevation of the same. Fig. 3 represents an enlargement of a portion of Fig. 2 with a part removed. Fig. 4 represents a

section on line 4 4 of Fig. 2. Figs. 5 and 6 50 represent perspective views hereinafter referred to. Figs. 7 and 8 represent, respectively, an end and a front elevation of a different embodiment of my invention. Fig. 9 represents a section on line 9 9 of Fig. 8. Fig. 55 10 represents a section on line 10 10 of Fig. 9.

The same letters of reference indicate the same parts in all the figures.

In the drawings, and referring for the present to Figs. 1 to 6, inclusive, *a* represents a 60 supporting base or standard the upper end of which is formed as an anvil *b*, the acting face or surface of which is preferably slightly concave. *c* represents a vertical standard which is formed on or affixed to the anvil *b* 65 and extends upwardly a considerable distance above the same, said standard being provided with an offset guide or projection *c'*, which extends over one end of the anvil, the said guide being separated from the anvil by a narrow slot or space *c*² of more than sufficient width to receive the thickness of the tire. *d* represents a dog which is vertically and laterally movable in the guide *c'* and is adapted to coöperate with the anvil in 70 grasping the tire. Said dog is pivotally mounted upon the lower ends of links *d'* *d*', which depend from and are pivoted to a slide *d*², movable vertically in the guide *c'*, whereby a substantially universal flexible connection is 75 secured. *d*³ represents an adjusting-screw, which is engaged with an internally-threaded bushing or nut *d*⁴, affixed to the guide *c'*, its lower end having a peripheral groove which receives the margin of an orifice *d*⁵, formed in 80 the slide *d*². The rotation of the screw *d*³ causes it to move endwise upwardly or downwardly, as the case may be, thus raising or depressing the slide *d*². The lower end of the links *d'* are provided with trunnions *d*⁶, which 85 enter sockets formed for their reception in the upper portions of the ends of the dog *d*, said upper portions having tapering recesses *d*⁷, Fig. 6, which permit the dog to tip on the trunnions *d*⁶. A spring *d*⁸ normally holds the 90 dog at one side of the passage or channel of the guide *c'*, said spring having an extension *d*⁹ bearing against the upper end of said dog,

as shown in Fig. 3. It will be seen that the dog d is positively moved in both directions by the adjusting-screw and is securely held by the latter at any position to which it may be 5 adjusted, there being no liability of the displacement of the dog through any slipping of the adjusting device. h represents a lever pivoted at h' to the upper end of the standard c . Said lever projects downwardly and has at 10 its lower end an offset portion h'' , the upper end of which constitutes an extension of the anvil b . The lever h has also an offset guide c' , in which a dog d'' is vertically and laterally movable, said dog coöperating with the offset 15 portion h'' of the lever h in grasping the interposed portion of the tire. The dog d'' is adjusted vertically by an adjusting-screw d^{10} , corresponding to the adjusting-screw d^3 , the screw d^{10} being connected with the dog d'' by 20 means similar to those which connect the screw d^3 with the dog d . j represents a short lever, which is pivoted at j' to the supporting-standard below the anvil and is connected by a rod or bar j'' with the portion h'' of the lever h , 25 said rod or bar extending through an opening formed in the standard a below the anvil b . On the lever j is formed an arm having a socket j'' to receive an elongated operating-lever j^4 .

30 The operation of the described machine is as follows: The portion of the tire t to be shortened or upset having been suitably heated, it is placed upon the anvil, the lever h being moved away from the anvil, as indicated in Fig. 2. 35 The dogs d d'' are depressed by the adjusting-screws and firmly clamp the tire against the anvil and the offset portion h'' of the lever, respectively. The operator then grasping the operating-lever j^4 exerts pressure in the 40 direction required to move the dog d'' toward the dog d , thus tending to bend or corrugate the interposed portion of the tire. The tire is continually hammered while this pressure is being applied, so that it is prevented from 45 bending, the material displaced by the pressure being kept in the arc of the tire by the hammering operation, the result being a shortening of the tire without change of its curvature.

I desire to call especial attention to the fact 50 that in my present device for the operation of the dogs d and d'' I employ a novel mechanism consisting of a screw having, preferably, a quick-running thread, whereby through the medium of the slide d^2 , the links d' , and the co- 55 acting dog d or d'' I am enabled to produce a device which will clamp quickly and let go easily, the dog or dogs clamping with the draw of the machine, which I have found in practice to greatly surpass prior devices 60 wherein have been shown a cam carrying a clamping dog or dogs directly upon the work. The employment of the links instead of the direct pivoting of the dog upon the relatively fixed nut on the screw enables me to provide

greater play for the dog or dogs and also al- 65 lows of independent movement of the lower end of the dog, which it would not have if the dog were pivoted directly to the aforesaid nut.

In Figs. 7, 8, 9, and 10 I show a machine embodying my invention in which the tire-grasping dogs instead of being arranged to bear upon the inner side of the tire are arranged to bear upon one edge of the tire, the dogs being movable toward and from the edge of the tire instead of the side. In this embodiment of my invention the machine is provided with the fixed vertical standard c , the fixed grooved bed b , the swing-lever h , and the offset portion h'' , forming a movable extension of the bed b , all as above described. The machine is also provided with means similar to those shown in Figs. 1 and 2 for moving the lever h and the movable bed toward and from the fixed bed. c^{10} represents a horizontal guide which is substituted for the fixed vertical guide c' . d^{100} represents a dog which is movable horizontally in said guide and is adapted to bear upon one edge of the tire t , as shown in Figs. 9 and 10. d^{12} represents a slide which is movable in the guide c^{10} and is 90 connected by hooked lugs or couplings d^{13} d^{13} with the dog d^{100} , the said couplings entering grooves d^{14} in the dog d^{100} and fitting said grooves loosely, thus forming a flexible connection, so that the dogs can rock independently, as in the construction shown in Figs. 3, 4, 5, and 6. d^{15} represents a horizontal adjusting-screw, engaged with a nut d^{16} , affixed to the guide c^{10} , the said adjusting-screw being engaged with the slide d^{12} in such manner 100 that the rotation of the screw will move the slide back and forth in the guide c^{10} . Between the inner end of the screw and the dog d^{100} is interposed a loose block d^{17} . The dog d^{100} is preferably composed of a series of independent sections s s , as shown in Fig. 9, the sections being placed side by side and all engaged in the manner above described with the couplings d^{13} . This sectional construction 110 gives the dog d^{100} a plurality of bearing edges adapted to bear simultaneously on the tire, each section being independent of the other, so that said bearing edges can adapt themselves to any undulations or irregularities in the surface of the tire on which they bear. 115 The sections s s , comprising the dog d^{100} , are normally pressed in one direction by means of a spring d^{18} . (See Fig. 9.) The offset portion h'' of the lever h has a horizontal guide c^{12} , in which a dog d^{20} is horizontally movable, said dog being adapted to bear on the edge of the tire like the dog d^{100} . The dog d^{20} is adjusted horizontally by an adjusting-screw d^{21} , corresponding to the adjusting-screw d^{15} , the screw d^{21} being connected with the dog d^{20} by means 120 similar to those which connect the screw d^{15} with the dog d^{100} . The dog d^{20} may also be made of independent sections s .

I claim—

1. In a tire-upsetting machine, a guide, a nut located in said guide, an adjusting-screw mounted in said nut, a slide in engagement with said screw, a dog supported in said guide, and links having their upper ends pivotally attached to said slide and their lower ends detachably connected to said dog, combined with a spring exerting lateral tension on the lower portion of said dog.

2. In a tire-upsetting machine, a guide, a nut located in said guide, an adjusting-screw mounted in said nut, a slide in engagement with said screw, a dog loosely suspended from said slide by a pivotal support whereby its upper and lower portions have independent movement, and means exerting a lateral tension on the lower portion of the dog.

15 3. In a tire-upsetting machine, an anvil,

guides adjacent thereto, slides in said guides, 20 links depending from said slides, dogs supported from said links, a spring bearing against a side of each dog, an adjusting-screw actuating each of said slides, and means for actuating said guides.

25 4. A tire-upsetting machine comprising a bed or anvil, a guide adjacent to the anvil, a slide movable in said guide, a tire-grasping dog composed of a plurality of independent sections side by side, means for connecting 30 the sections with the slide and a dog-adjusting screw engaged with said slide.

In testimony whereof I have affixed my signature in presence of two witnesses.

LEONARD F. FAIRBANKS.
